UNITED STATES PATENT OFFICE.

WILLIAM F. LAUTENSCHLAGER, OF CINCINNATI, OHIO, ASSIGNOR TO LORENZ MUTHER, OF NEWTON, MASSACHUSETTS.

MEMBER FOR SHOE-UPPERS.

1,351,722.

Specification of Letters Patent. Patented Aug. 31, 1920.

Application filed October 20, 1917. Serial No. 197,611.

To all whom it may concern:

Be it known that I, WILLIAM F. LAUTENSCHLAGER, a citizen of the United States, and residing at Cincinnati, in the county of 5 Hamilton and State of Ohio, have invented a new and useful Member for Shoe-Uppers, of which the following specification is a full disclosure.

My invention relates to a member for a 10 shoe upper, or similar article, where two sheets are to be held together for unitary manipulations, in a manner permitting some degree of relative movements of the sheets, as in the folded margin of a shoe upper.

15 The object of the invention is to produce a sheet article, such as a shoe upper part, comprising superposed shoe parts, such as the margins of a shoe upper, adhesively united to an intermediate member, such as a 20 folded tape, enabling the superposed parts to be manipulated as a unitary member, while providing slight relative movement between the superposed members.

25 The features of the invention will be more fully set forth in the description of the accompanying drawings, forming a part of this specification, wherein:

Figure 1 is a perspective view, partly in section, showing a lasted shoe upper.

30 Fig. 2 is a plan view of the shoe upper, showing my method of edge folding.

Fig. 3 is an enlarged perspective section, showing the skived portion of the marginal edges.

35 Fig. 4 is an enlarged perspective section of the folded adhesive tape used in my method.

Fig. 5 is an enlarged perspective section on line 5—5, Fig. 2.

40 Fig. 6 is an enlarged perspective section on line 6—6, Fig. 2.

Fig. 7 is an enlarged perspective section on line 7—7, Fig. 1.

45 The finish edges of shoe uppers, generally, terminate in skived edges and such edges are ordinarily folded inwardly and secured by cement. This cementing operation is expensive and slow and is frequently ineffective for retaining the edge in folded condition during the subsequent stitching operation.

50 The method I preferably employ for producing my new article consists in taking a strip of tape folded upon itself to constitute the insert 1, only the exterior surfaces hav-

ing adhesive application, much cheaper than cement. This insert is placed along the skived portion 2 with free edges 3 coincident to the line of fold and the folded tape edge 4 pointing inwardly. The skived portion of 60 the upper is bent over this insert, as indicated in Fig. 5, both inner surfaces of the upper margin being adhesively secured to and retained by the adhesive surfaces of the folded tape, the normal line of finishing 65 stitches being shown by dotted lines 5, Fig. 5. This insert and folding operation can either be done by hand or machinery, and, if the latter, the tape folding and inserting can be run along coördinately with the 70 machinery for folding over the upper margin.

This constitutes a satisfactory, temporary 75 securance, the process is much cheaper and cleaner than the cementing treatment and the finished product is better because the margin is advantageously reinforced by this folded tape insert.

The member so made is primarily intended for application to straight edges of an upper, tip, or vamp, or to long curves, 80 and is not intended particularly for relatively sharp curves. As, for instance, the same method and structure may be employed for the vamp edge 6 and tip edge 7, and the saving of labor are material items. 85

The outer surfaces of the folded tape when moistened adhere to the inner folded surfaces of the upper and so constitute a marginal reinforcement of value in preventing the stitches from pulling out, and also 90 produces a superior finished appearance as well as a more durable shoe.

The flat character of the folded tape insert, provides a reinforced margin into which the needle of the stitching machine 95 will readily take, drawing the stitch through two thicknesses of the upper, vamp or tip, and the two wings of the folded tape, forming a stout stitch anchorage. The tape may be wide enough to project below the folded 100 over upper edge, or it may terminate flush with this down turned upper edge.

Preferably a wide tape is employed in the folded top edge 8 of the shoe upper. This wide tape extends approximately twice the 105 width of the fold (see Fig. 6), and when the lining 9 is assembled with the upper, the exposed portion 10 of the adhesive tape surface is moistened, serving as an anchorage for the lining previous to stitching, (see 110

Fig. 7), and as a reinforcement for the top of the finished shoe.

Having described my invention, I claim:—

1. A shoe upper member having a marginal edge folded over, and a folded tape having adhesive exterior surfaces secured within the shoe material fold, the folded edge of the tape being outermost.
2. A shoe upper member having a marginal edge folded over, and a folded tape having adhesive exterior surfaces, lying within the folded margin, the folded edge of the tape coinciding with the turned over edge of the material, and the double edges 15 of the tape coinciding with the fold of the material.
3. A shoe upper member having a margin folded upon itself, and an adhesive tape placed within the fold to aline a medial free 20 portion of the tape with the turned edge of the upper member.

4. A sheet article of the nature disclosed, having a base member and overlying member, and an intermediate adhesive member securing them together and placed to aline 25 a medial free portion of said member with the edge of the member overlying the base member.

5. A sheet article of the nature disclosed, 30 comprising superposed members, and a flexible intermediate adhesive member uniting the superposed members and having a medial free portion permitting slight relative movement between the superposed members.

In witness whereof I hereunto subscribe 3 my name, as attested by the two subscribing witnesses.

WILLIAM F. LAUTENSCHLAGER.
